UNITED STATES PATENT OFFICE.

AARON SIMON, OF BROOKLYN, AND LOUIS YENTIS, OF JACKSON HEIGHTS, NEW YORK.

DESIGN FOR A CIGAR LIGHTER OR SIMILAR ARTICLE.

Application filed June 5, 1928. Serial No. 27,008. Term of patent 3½ years.

To all whom it may concern:

Be it known that we, AARON SIMON and LOUIS YENTIS, citizens of the United States, residing, respectively, in New York city, borough of Brooklyn, Kings County, New York, and Jackson Heights, Queens County and State of New York, have invented a new, original, and ornamental Design for a Cigar Lighter or Similar Article, of which the following is a specification, reference being had to the accompanying drawings, forming a part thereof, and in which:

Fig. 2 is an elevation of the opposite side of the article showing our new design;
Fig. 3 is a top plan, and
Fig. 4 is a bottom plan.

We claim:

The ornamental design for a cigar lighter or similar article, as shown.

AARON SIMON.
LOUIS YENTIS.
